UNITED STATES PATENT OFFICE

133,702

DESIGN FOR A NEON TUBULAR SIGN

Donald McAfee, San Mateo, and Sam Gisnet,
San Francisco, Calif., assignors to Pacific Brew-
ing & Malting Co., San Jose, Calif., a corpora-
tion of California

Application April 11, 1941, Serial No. 100,325

Term of patent 3½ years

To all whom it may concern:

Be it known that we, Donald McAfee, a citizen of the United States, residing at San Mateo, in the county of San Mateo and state of California, and Sam Gisnet, a citizen of the United States, residing at San Francisco, in the county of San Francisco and State of California, have jointly invented a new, original, and ornamental Design for Neon Tubular Signs, of which the following is a specification, reference being had

to the accompanying drawing, forming a part thereof.

Fig. 1 is a front elevation and

Fig. 2 is a plan view of a neon tubular sign, showing our new design.

We claim:

The ornamental design for a neon tubular sign, as shown.

DONALD McAFFEE,
SAM GISNET.
